CLOSURE FOR CARTONS

Elmore J. Bonner, Memphis, Tenn.

Application August 22, 1936, Serial No. 97,458

7 Claims. (Cl. 229—17)

This invention relates to the class of material containers or cartons and particularly to improvements in closures therefor.

The primary object of the present invention is to provide an improved dispensing means and closure for cartons, particularly those of the type employed for packaging groceries such as sugar, cereal, corn flakes, or similar substances, or materials of the nature of soap flakes, soap powders, etc., where the use is made of the regular flap portions of the carton in the formation of the dispensing opening and the means whereby the same may be covered or uncovered.

Another object of the invention is to provide in a carton structure a material dispensing opening having a sliding cut-off whereby the contents may be readily dispensed and whereby the dispensing opening may be tightly closed to prevent the entrance of contaminating substances.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:

Figure 1 is a view in plan of one end of the carton blank showing the manner of forming the improved dispensing opening and shut-off means therefor, the figure including the shut-off slide.

Fig. 2 is a view in perspective of a carton showing the end flaps partly folded in the process of assembling the device.

Fig. 3 is a view in plan of the nature of the carton illustrated in Fig. 2, but showing an additional step in the formation of the same.

Fig. 4 is a view similar to Fig. 3, but showing the next step in assembling the device which comprises the placing of the cut-off slide in position.

Fig. 5 is a view in end elevation of the folded structure showing the slide drawn out to uncover the dispensing opening, a portion of the outer flap being broken away to show the relation of the slide with the other parts.

Fig. 6 is a section on the line 6—6 of Fig. 5.

Fig. 7 is an end view similar to Fig. 5, but illustrating the use of the tear-out portions in the dispensing opening and the opening provided for engaging the finger with the slide.

Referring now more particularly to the drawings wherein like numerals of reference designate corresponding parts throughout the specification, the numeral 1 generally designates an end of a box or carton constructed in accordance with the present invention, the numerals 2 and 3 designating the side walls and the numerals 4 and 5 designating the edge walls. At the ends of the side and edge walls are the usual carton flaps which under normal conditions are imperforate and are folded in one over the other to form the end wall of the carton, these flaps being designated by the numerals 6, 7, 8 and 9.

In carrying out the present invention, one of the flaps which is to lie upon the outside of the end of the box carton, for example the flap 6, is provided with a rectangular opening or an opening of any other desired configuration, as indicated at 10. This opening is made adjacent one end of the flap and at the opposite end a recess 11 is cut in the edge of the flap. The flap 7 is provided with an opening or recess 12 which is designed to co-operate with the recess 10 and is of the same width.

The flap 8 has an elongated recess cut therein as indicated at 13, from the end remote from the flap 7. This end recess has one side straight throughout while the other side has an offset adjacent the open end of the recess forming the shoulder 14, and from this shoulder to the open end of the recess the recess is of less width than from the shoulder to the opposite end. The material cut out in forming the elongated recess 13 is employed for the shut-off slide, and is indicated by the numeral 15. This slide through a portion of its length from one end is of a width equal to the greatest width of the recess 13 and through the remainder of its length it is of a width equal to the narrowest portion of the recess 13 so that there is formed a stop shoulder 16 at one side of the slide, as indicated at 16. The portion of the slide of lesser width is materially longer than the portion of the recess 13, which is of narrowest width, and the entire or over-all length of the slide is equal to the over-all length of the recess 13. Thus it will be apparent that when the slide 15 is disposed in the recess 13, there will be an open space between the shoulders 14 and 16 as indicated by the numeral 17 of Fig. 4.

The flap 9 remains unchanged in that it is not cut but it is provided along each side edge upon the top surface with an application of adhesive, as indicated by the numeral 18.

The slide 15 and consequently the recess 13, is

of a width greater than the width of the dispensing opening 10 and the recess 12, while the top surface of the intermediate flap 8 is provided with a coating of adhesive, as indicated at 19. The 5 top surface of the flap 7 is provided upon its top surface with a narrow band of adhesive which extends inwardly from the side edges and from the inner edge fold line as indicated at 20. The top surface of the flap 7 has a portion uncovered 10 by the adhesive which is of a width equal to the width of the slide 15 and this uncovered portion extends also across the inner end of the recess 12.

In assembling the box or carton constructed in accordance with the present invention, the four 15 side walls are arranged so that the edge flap 21 which forms an integral part of the long outer edge of the side wall 2 can be brought into abutting relation with the inner side of the edge wall 5 to form the carton in the usual rectangular outline. The end flaps 7 and 9 which are at the ends 20 of the edge walls 4 and 5 respectively are then turned in, as illustrated in Fig. 2. The adhesive surfaces 18 and 20 of these end flaps are then moistened and the intermediate flap 8 is then 25 folded in, as illustrated in Fig. 3.

The next step in the forming of the dispensing end wall structure of the carton comprises placing the slide 15 in the long recess of the flap 8 as shown in Fig. 4. It will be noted from Figs. 3 30 and 4 that portions of the flap 7 bordering the recess 12 extend in beyond the side and end edges of the recess 13 thus forming the supporting shoulders 22 for the inner end of the slide 15 while the outer end rests upon the central part 35 of the flap 9. Following this step the adhesive surface 19 is moistened and the top or outer flap 6 is then folded down over the slide giving the final structure, as illustrated in Fig. 5. The slide 40 15 is provided with a notch or an aperture at the point 23 which will be located in the recess 11 when the slide is moved inwardly in the recess 13 to the point where it completely fills the latter and covers the opening 10. Since the opening 10 and the recess 12 are in flaps which are held in 45 spaced relation by the flap 8 where the recess 13 is of greater width than the recess 12 and the opening 10, it will be apparent that the inner or forward end of the slide 15 will have its edges slidably held so that when the opening 10 is covered no dust or foreign matter can get past the 50 slide into the carton.

Fig. 6 illustrates this enclosing recess for the edge of the slide 15, the recess being indicated by the numeral 24. It will also be seen from Figs. 4 55 and 5 that the outward movement of the slide 15 is limited by the overlapping relation of the shoulders 14 and 16, the shoulder 16 striking the shoulder 14 when the slide is pulled out so as to stop it at the point where its forward edge will be in 60 a line with the nearest transverse edge of the opening 10.

Fig. 7 illustrates a slightly modified form of the dispensing structure of the carton. In this figure the outer or top flap corresponding to the flap 6, is indicated by the numeral 25, and the dispensing opening as well as the recess provided to facilitate engaging the end of the slide, are merely outlined by the perforations 26 and 27. When the 65 carton is to be opened, the portions lying within the perforated areas can be removed by merely breaking the parts of the paper between the perforations so that the central part of the flap can be removed, thus giving a structure like that illustrated in Fig. 5.

75 From the foregoing it will be readily apparent

that in addition to providing a novel dispensing means for a carton and means for effectively closing the same, an economical method has been devised whereby this desirable structure may be obtained without necessitating the use of any 5 additional carton material. Use is made entirely of the parts which would go into the construction of the box if it were made in the usual way with the four flaps arranged in overlapping relation to form the box end wall. 10

What is claimed, is:

1. In a box or carton, an end wall comprising an inturned flap and a second flap lying therebeneath, said first flap having means for dispensing material therethru, said second flap having a 15 recess cut thereinto from and opening through one edge and extending thru the major extent of the flap toward the other edge whereby the said dispensing means overlies the inner end of the recess, a shut-off slide lying in said recess and having 20 limited movement longitudinally therein to cover or uncover said dispensing means, and means by which the slide is maintained in the recess in the plane of the second flap.

2. In a box or carton, an end wall comprising 25 two inturned flaps lying one over the other, the outer one of said flaps having a dispensing opening, the inner one of said flaps having an elongated strip removed from the central portion thereof and extending through one edge, said removed portion constituting a shut-off for said dispensing opening, and means associated with the second mentioned flap for maintaining the removed strip of material in sliding relation with the flap from which it was removed whereby it 30 may be moved into covering or uncovering relation with the dispensing opening.

3. In a box or carton, an end wall comprising 35 two inturned flaps arranged in superimposed relation, the outer one of said flaps having a material discharging opening, the inner one of the flaps having an elongated recess cut thereinto from and opening thru one edge, said recess extending beyond the dispensing opening of the upper flap, a shut-off slide disposed in said recess and constantly maintained throughout its length in the plane of the inner flap, means for retaining the slide in position in the recess and permitting its longitudinal movement, the slide when shifted in one direction having an end extending outwardly 40 beyond the side edge of the second-mentioned flap, and means forming a stop for limiting the outward movement of the slide relative to the discharge opening.

4. In a box or carton, an end wall comprising 45 two inturned flaps arranged in superimposed relation, the outer one of said flaps having a material discharging opening, the inner one of the flaps having an elongated recess cut thereinto from one edge, said recess extending beyond the dispensing opening of the upper flap, a shut-off slide disposed in said recess in the plane of the inner flap, means for retaining the slide in position in the recess and permitting its longitudinal movement, the slide when shifted in one direction having an end extending outwardly beyond said edge of the second-mentioned flap, said recess adjacent the open end thereof being of reduced width through a portion of its length whereby an inwardly extending shoulder is formed in one longitudinal edge, and said slide being of a reduced width through a portion of its length to position in the portion of reduced width of the recess, the reduced portion of the slide forming with the wider portion thereof a stop shoulder designed 50

75

to co-act with the stop shoulder in the edge of the recess to limit the movement of the slide.

5. In a box or carton, an end wall consisting of two inturned flaps disposed in a common plane and two flaps arranged in superimposed relation over the first-mentioned flaps, one of said first-mentioned flaps and the outer one of the superimposed flaps having coinciding material-discharging openings, the inner one of the superimposed flaps having an elongated recess therein which opens through an edge of the flap remote from said openings, said recess being of slightly greater width than the openings and extending slightly beyond the side of the openings remote 10 from the open end of the recess, and a slide body disposed in said recess between the outer one of the superimposed flaps and the two first-mentioned flaps, the said slide body being coplanar with the recessed flap and of a width greater than 15 said coinciding openings from the end adjacent the openings through an extent lengthwise of the slide sufficient to completely cover the openings when the slide is shifted to the limit of its movement in the recess toward the closed end thereof.

20 6. In a box or carton, an end wall consisting of two inturned flaps disposed in a common plane and two flaps arranged in superimposed relation over the first mentioned flaps, one of said first-mentioned flaps and the outer one of the superimposed flaps having coinciding material-discharging openings, the inner one of the superimposed flaps having an elongated recess therein which opens through an edge of the flap remote from said openings, said recess being of slightly 25 greater width than the openings and extending slightly beyond the side of the openings remote from the open end of the recess, a slide body disposed in said recess between the outer one of the superimposed flaps and the two first-mentioned flaps, the said slide body being coplanar with the recessed flap and of a width greater than said coinciding openings from the end adjacent the 30

35

40

openings through an extent lengthwise of the slide sufficient to completely cover the openings when the slide is shifted to the limit of its movement in the recess toward the closed end thereof, and means facilitating the engagement by a finger of the end of the slide remote from the dispensing openings whereby the slide may be shifted longitudinally to uncover said openings the slide being retained flat throughout its length and in co-planar relation with the recessed flap by the two first-mentioned flaps and the outer one of the superimposed flaps, the slide being of a width greater than said coinciding openings through a portion of its length from the end adjacent the 10 15 20 25 30 35 40

7. In a box or carton, an end wall consisting of two inturned flaps disposed in a common plane and two flaps arranged in superimposed relation over the first-mentioned flaps, one of said first mentioned flaps and the outer one of the superimposed flaps having coinciding material-discharging openings, the inner one of the superimposed flaps having an elongated recess therein which opens through an edge of the flap remote from said openings, said recess being of slightly greater width than the openings and extending slightly beyond the side of the openings remote from the open end of the recess, a slide body disposed in said recess between the outer one of the superimposed flaps and the two first-mentioned flaps, the said slide body being coplanar with the recessed flap and of a width greater than said coinciding openings from the end adjacent the openings through an extent lengthwise of the slide sufficient to completely cover the openings when the slide is shifted to the limit of its movement in the recess toward the closed end thereof, and co-acting means between an edge of the slide and the adjacent edge of the recess limiting the longitudinal movement of the slide in one direction relative to the dispensing openings.

ELMORE J. BONNER.
